NEVER-SLIP CORSET HOLDER

Mae G. Walz, San Antonio, Tex.

Application December 20, 1939, Serial No. 310,227

2 Claims. (Cl. 241—1)

This invention relates to a never-slip corset holder.

An object of the invention is the construction of a novel and efficient device for holding a girdle or corset down in position without the use of hosiery.

Another object of the invention is the provision of means for holding a corset in place, without using the hose, as the hose is usually too expensive for this purpose, and too, where short hose, such as knee length are worn.

A still further object of the invention is the construction of a holder which can be made to fit the leg snugly, and which is provided with novel means for attaching the fastening means of the corset strap, and maintaining the fastening means in position without injuring or causing any discomfiture to the wearer.

With the foregoing and other objects in view, my invention comprises certain novel constructions, combinations, and arrangements of parts as will be hereinafter fully described, illustrated in the accompanying drawing, and more particularly pointed out in the appended claims.

In the drawing:

Figure 1 is a view in elevation of two of the holders constructed in accordance with the present invention shown upon the legs of a person.

Figure 2 is an enlarged view, partly in elevation and partly in vertical section.

Figure 3 is a horizontal sectional view taken on line 3—3, Figure 2, and looking in the direction of the arrows.

Figure 4 is an enlarged sectional view taken on line 4—4, Figure 2, and looking in the direction of the arrows.

Referring to the drawing, in which I have shown the preferred embodiment of my invention, 1 designates an elastic surrounding body, and 2 is a suitable lining therein; this lining 2 can be made from silk or any like material. The lining at 3, Fig. 3, is full, being over the fastening means 4, that is provided for closing the slit or opening 5. Therefore, it will be understood that the lining 2 permits suitable expansion and contraction of the surrounding body 1.

The slit 5 does not extend to the top edge of the elastic body 1, but does extend to its lower edge, and while I have shown a lacing as fastening means 4, other common means, such as a Zipper, may be used, for opening and closing the slit, if the operator desires.

Around the elastic body 1, and at its lower edge, is a reinforcing band 6, which is sewed, or otherwise fastened to the elastic body, and is pro-

vided with an end 7 overlapping (see Fig. 4) the other end of the band, and this end 7 is provided on its inside with a hook 8 that is adapted to engage one of the eyes 9, for more positively fastening the holder in an adjusted position upon the leg, although very satisfactory results will be obtained, without utilizing the band, by reason of the elastic body snugly fitting the leg when placed thereon.

A flounce band 10 is fastened at its inner edge to the upperedge of the elastic body. This novel flounce band is very useful, in providing means free from the leg to which the fastening means 11 of corset strap 12 is attached. As seen in Fig. 2, the fastening means is free from the leg and does not contact it, thereby eliminating an undesirable feeling. If attachment of fastening means 11 was attempted directly to the top of the body 1 this would be very unsatisfactory, for then the fastening means 11 would be rubbing or bearing against the skin of the wearer. However, this is entirely obviated by my novel construction.

The holders can be adjusted for any size of leg, and can be also adjusted vertically on the leg, to accommodate different types of corsets or girdles. Further, by using my novel holders the wearer will have an admirable means for holding the corset or girdle in position, irrespective as to whether the wearer has on any hose, long hose, or short hose, or socks.

While the elastic surrounding body will grip or bind the leg in a gentle manner, by closing the slit 5 and hooking up tightly the reinforcing band 6, the holder will be caused to rest snugly in a permanent adjusted position upon the leg.

The flounce band 10 gives freedom all around the top of the holder, at any point of which band the corset straps may be attached, with no disagreeable effect or annoyance to the wearer. This flounce band is usually folded over the upper edge of the elastic body (see Fig. 2) and these folded-in edges are fastened together by a line of stitching 13.

Therefore, the fastening means 11 grip the top edge of the flounce band 10, which top edge is double in thickness, by reason of the band being folded, as will be clearly seen upon referring to the left-hand end or edge of the band in Fig. 2.

While I have described the preferred embodiment of my invention and illustrated the same in the accompanying drawing, certain minor changes or alterations may appear to one skilled

in the art to which this invention relates during the extensive manufacture of the same, and I, therefore, reserve the right to make such changes or alterations as shall fairly fall within the scope of the appended claims.

What I claim is:

1. In a device of the class described, the combination of a comparatively wide elastic surrounding body provided at one edge with an inwardly extending slit, means for fastening or closing said slit together, a flounce band fastened at its inner edge to the upper edge of said surrounding body, a reinforcing band fastened to the lower portion of said body and having an end overlapping said slit, and said overlapping end 15

and a portion of said band provided with registering fastening means.

2. In a device of the class described, the combination of a comparatively wide elastic surrounding body provided at one edge with an inwardly extending slit, a lining within said body and puckered over said slit, whereby the lining is permitted to expand with the expansion of said surrounding body, a flounce band fastened at its 10 inner edge to the upper edge of said surrounding body and lining, a reinforcing band fastened over the lower edge of said surrounding body, and means for closing said slit, substantially as shown and described.

MAE G. WALZ.
